UNITED STATES PATENT OFFICE.

JOSIAH H. MEAD, OF NEW YORK, N. Y.

DESIGN FOR A GAS STEAM-RADIATOR.

No. 39,827.

Specification for Design.

Patented Feb. 16, 1909.

Application filed August 22, 1908. Serial No. 449,884. Term of patent 7 years.

To all whom it may concern:

Be it known that I, JOSIAH H. MEAD, a citizen of the United States, residing at New York city, in the county of New York and State of New York, have invented a new, original, and ornamental Design for Gas Steam-Radiators, of which the following is a specification, reference being had to the accompanying drawings, forming part thereof.

The figure is a perspective view of the structure showing the new and ornamental design.

The design is especially applicable to the base 1 and to the ornamental scroll work as shown both on the sides and ends, the said ends having their side scroll extended to form supports or legs 2. The radiator used above the base is similar to radiators already in use and is composed of a plurality of sections or coils 3 with corners rounded as

shown and with the end coils provided with depressions or indentations 4 with bolt heads 5 with such indentations, and a vertical groove 6 extending longitudinally of and substantially in the center of the end coil and terminating both at the upper and lower ends in enlarged depressions or circles 7 within which as a center bolt heads 8 are seated.

While the radiator coils are not in themselves novel, such radiator coils with the base represented complete as a whole is claimed as a novel and ornamental design.

I claim:

The ornamental design for a gas steam radiator, as shown and described.

JOSIAH H. MEAD.
